GRINDING MACHINE

Frederick S. Haas, Cincinnati, Ohio, assignor to
 Cincinnati Grinders Incorporated, Cincinnati,
 Ohio, a corporation of Ohio

Application May 12, 1932, Serial No. 610,837

16 Claims. (Cl. 51—103)

This invention relates to improvements in machine tools and especially to improvements in grinding machines of the centerless type.

An object of the invention is the provision of improved means for supporting and guiding a work piece through the throat of a centerless grinder.

Another object of the invention is the provision of improved means adjustable through a plurality of planes of adjustment for adapting the machine for grinding all sizes of work pieces within the range thereof.

A further object of the invention is the provision of variable adjustable guides, work rest, and overhead shoe for use with a centerless grinder between the opposed grinding and regulating wheels thereof for adapting the machine for operation on a plurality of sizes and types of work pieces.

Other objects and advantages of the present invention should be readily apparent by reference to the following specification, considered in conjunction with the accompanying drawings, forming a part thereof, and it is to be understood that any modifications may be made in the exact structural details there shown and described within the scope of the appended claims without departing from or exceeding the spirit of the invention.

30 In the drawings:

Figure 1 is a side elevation of a grinding machine embodying the improvements of this invention.

Figure 2 is a front elevation of the machine shown in Figure 1 and as particularly seen by looking directly into the grinding throat.

Figure 3 is a transverse sectional view through the grinding throat and as seen substantially from line 3—3 on Figure 1.

Figure 4 is a sectional view taken on line 4—4 of Figure 3.

Figure 5 is a sectional view taken substantially on line 5—5 of Figure 2.

Figure 6 is a sectional view taken substantially on line 6—6 of Figure 5.

Figure 7 is a sectional view taken substantially on line 7—7 of Figure 6.

Figure 8 is a fragmentary sectional view taken on line 8—8 of Figure 3.

Figure 9 is a fragmentary sectional view taken on line 9—9 of Figure 3.

Throughout the several views of the drawings similar reference characters are employed to denote the same or similar parts.

As shown in Figure 1, the machine is provided

with an operative surface extending at an acute angle to the vertical and comprises a bed 10 having formed along this acute angle guideways 11 for a grinding wheel carriage 12 to guide same in its movement relative to the bed. The carriage 12 has journaled therein a spindle 13 to one end of which is secured a grinding wheel 14. Secured to the spindle 13 is a pulley 15 having trained thereabout a belt or other flexible transmission 16 in turn extending about a pulley 65 secured to a countershaft 17 carried by an arm 18 journaled on a shaft 19 supported by the bed 10. The shaft 17 is provided with a second pulley 70 about which extends a belt or other flexible transmission 20 in turn journaled about a pulley or sheave 21 secured to the motor or motor shaft 22 of the electric motor or other prime mover 23. This motor 23 is suitably supported by a bracket 24 formed integral with or positioned interiorly of the bed 10. The motor 23 through the flexible transmissions or belts 20 and 16 is adapted to rotate the spindle 13 and grinding wheel 14 at a high grinding rate of speed in a clockwise direction as indicated by the arrow associated therewith.

In order to shift the grinding wheel carriage 12 and grinding wheel 14 relative to the guideways 11, it has depending from it a lug or arm 25 in which is journaled a nut 26 in threaded engagement with an adjusting screw 27 fixed 85 against axial movement relative to the bed as by bearings 28 and 29. Secured to or integral with the nut 26 is a worm wheel 30 meshing with a worm 31 on the end of the shaft 32 extending through and carried by the guide 12. 90 The shaft 32 has on its outer end a hand wheel 33 whereby it is rotated for effecting the relative adjustment of the carriage 12. The grinding wheel 14 is enclosed within a suitable guard or housing 34 forming a guideway 35 for a truing tool or the like 36 adapted to be traversed across the active face of the grinding wheel to maintain same in a true, sharp condition.

The bed 10 is further provided along its operative inclined surface with a housing or bracket 37 to which is secured a head 38 enclosing a spindle, carrying on its one end a regulating wheel 39. The regulating wheel 39 and its spindle are adapted to be rotated during the grinding operation at a relatively slow work rotation controlling rate of speed in a clockwise direction as indicated by the arrow associated therewith. The regulating wheel has its operative surface spaced a predetermined distance from the operative face of the grinding wheel 14 for 110

thereby forming a grinding throat of a size representative of the final size of the work being ground. In order to maintain the active face of the regulating wheel in a true, sharp condition, 5 the head 38 has secured thereto a bracket 40 for guiding a truing mechanism 41 while being traversed across the operative face of the regulating wheel.

The bed 10 is provided intermediate the part 10 to which the bracket 37 is attached and the guideways 11, with a boss 42 on which is formed a dove-tailed guide tongue 43 received in a similarly shaped guideway 44 formed in a bracket or block 45. The block 45, as shown in Figures 6 15 and 7, has journaled therein a shaft 46 having formed on its inner end a pinion 47 meshing with the teeth of a rack 48 secured to the dove-tailed guide 43. A gib 49 is interposed between one side of the guide 43 and the adjacent side 20 of the guideway 44 for taking up all play or lost motion that may exist between said parts. The gib being adjustable for varying its position and being adapted to be locked in adjusted position by means of a sliding clamp 50 abutting 25 on one end with one face of the gib and on the other end with a screw 51 threaded into the block or carriage 45.

The outer end of the shaft 46 is provided with a worm wheel 52 meshing with a worm 53 formed 30 integral with or secured to the worm shaft 54. This shaft 54 is journaled in a housing or boss 55 secured to the outer surface of the block or carriage 45. The end 56 of the worm shaft 54 is of angular cross section for the reception of 35 a suitable crank or the like and whereby the worm shaft may be rotated. From this it will be seen that rotation of the worm 53 will cause the rotation of the shaft 46 causing the rack pinion to advance along the rack 48 and carry 40 with it the block or carriage 45 for positioning same relative to the bed and the grinding throat. The carriage 45 is provided at its forward end with an upstanding flange 57 through which is formed elongated perforations 58 for bolts 59 which enter a block 60 for clamping said block 45 in adjusted positions relative to the flange 57. The means for adjusting this block 60 relative to the flange 57 will be described in detail later.

The block 60 is adapted to have secured therein 50 a blade 61 carrying as at 62 a wear strip or spot of hard material which is provided with an inclined operative surface 63 inclined in the general direction of the operative surface of the regulating wheel forming therewith a work receiving trough 55 in which the work piece to be operated upon is mounted or positioned. The blade 61 is secured in the block 60 by means of clamp screws or bolts 64 extending through one side thereof into engagement with the blade 61, which in actual practice is positioned in a slot or pocket 65 formed in the upper end of the block 60. To prevent dirt, grit, coolant or the like from having access to the guide 43 and way 44, the block 60 has pivoted, as at 66, a guard or shutter 67 which, as shown in Figure 5, is adapted to overhang the end of the boss or lug 42 when the carriage 45 is advanced to its forward end, but which, when the carriage is retracted, rides up the forward face of said lug 70 and overlies the operative surfaces of the guide and way 43 and 44. To prevent the above mentioned foreign materials from passing between the hinge 66 and adjacent surfaces of the block, the block is further provided with a flexible shutter 68 secured at one end to the block 60 and

having its other end received in a pocket 69 formed on the outer face of the guard 67.

From this it will be seen that the carriage guideway is effectively protected from the usual coolant and grit normal with grinding machines to thereby increase the accuracy and life of said guides.

As was noted above, the work rest blade 61 has an inclined operative surface 63 inclining in the general direction of the operative surface of the regulating wheel and forms therewith a work receiving trough. In alignment with the operative face of the wheel for guiding the work to the blade and receiving the work therefrom as it passes beyond the grinding throat, there is provided guide plates 70 and 71 respectively mounted at the forward and rear ends of the throat. The guide plates and their supporting and adjusting mechanisms are identical and it is deemed sufficient if but one of them be described in detail. 85 The guide plate 70 has its upper and lower edges beveled as at 72 and 73 in Figure 5. The beveled edge 72 of the plate 70 is received in the correspondingly beveled ways 74 formed in the lower ends of arms 75 and 76 integral with a bracket or support 77. The bracket or support 77 has formed intermediate its bounds an inclined counterbore 78 and a threaded perforation 79 in axial alignment with the bore 78. The axis of the bore 73 and perforation 79 extends in a direction that 90 is normal to the inclined edge 73 of the plate 70. A relatively large headed screw 80 is threaded into the perforation 79 utilizing the under flat surface of the head 81 thereof to engage with the bevel surface 73 for forcing the plate 70 into the ways 100 74 formed in the arms 75 and 76 for securing said plate in desired guiding position.

In order to adjust the bracket 77 and plate 70 to maintain alignment of the said plate with the operative face of the regulating wheel, as when the said wheel is worn or trued down, the bracket 77 has formed integral therewith a sleeve 82 extending into a cylindrical guide 90 formed integral with or secured to the head 38. The sleeve 78 has at one end an enlarged counterbore 83 providing a shoulder 84 against which is seated the adjacent surface of a collar 85 formed on an adjusting screw 86 that extends through the sleeve 82. One end of the screw 86 projects beyond the bracket 77 and has secured thereto a knob 87 whereby the screw is actuated. The knob 87 is further utilized for securing the shaft 86 to the bracket 77 by substantially clamping the said screw between itself and the collar 85. The adjusting screw 86 is provided further with a 115 threaded portion 88 beyond the collar 85, which is received in a nut 89 secured in the rear end of the cylindrical guide 90. In order to prevent inadvertent movement of the sleeve 82 relative to the guide 90, it has mounted therein a clamp screw 120 91 for securing the sleeve 82 and parts associated therewith in adjusted positions.

To prevent oscillatory movement of the bracket 77, as about the axis of the sleeve 82, the said bracket has projecting from it a guide stem 92 which passes through a guide boss 93 formed integral with or secured to the cylindrical guide 90.

It is frequently desirable to adjust the guide plates to dispose the guiding surfaces thereof at 145 an angle to the plane of extent of the operative face of the regulating wheel; this adjustment being also advantageous to correct for slight machining errors and to very minutely adjust the parts for correct work production. For this rea- 150

son, the bracket 77, see Figures 3 and 4, has journaled in its opposite vertical edges adjusting screws 94 and 95, each having an inclined wedge-like operative surface 96. The wedge surfaces 96 form the base against which the guide plate 70 is forced by the clamping screw 80. The said wedge screws 94 and 95 have each projecting from its rear surface a pin 97 extending into a guide slot 98 formed in the body of the bracket 77 to prevent 10 rotative movement of the wedge screws relative thereto. The bracket 77 is provided on opposite surfaces near the upper edge with slots 99 and 100 in each of which is disposed a nut 101 and 102 in threaded engagement with the wedge screws 94 15 and 95. In the event it is desired to elevate one or the other end of the guide plate 70, the clamp screw 80 is first loosened and then the proper nut 101 or 102 rotated for shifting its screw axially of the bracket 77 and thereby either raising or 20 lowering the said end of the guide plate 70.

In order to insure the work being properly steadied and guided while in the grinding throat, there is provided a blade or shoe 103 engaging with the work at a point substantially diametrically opposed to the point of contact of the work with the angle top 63 of the blade 61. The shoe 103, as seen in Figure 5, is connected by means of cap screws 104 and 105 to a block 106 having formed on its inner end a guide tongue 107 received in guide groove 108 formed along the adjacent face of support arm 109. It will be noted that the operative surface of the arm 109 is inclined toward the grinding wheel so that adjustment of the block 106 along this surface will cause the shoe 103 to remain in a normal position relative to the axis of the work while approaching or receding the operative faces of the wheels. This adjustment is utilized when different diameters of work pieces are to be ground by the machine. For example, if a work piece of a diameter less than that illustrated in Figure 5 were to be operated upon, the block 106 would be actuated downwardly toward the left as respects the operative surface of the arm 109. This would cause the shoe not only to be lowered vertically toward the axis of the work, but also to be adjusted toward the left since a smaller work piece would have its axis shifted toward the left, as seen in Figure 5. It being understood, of course, that the work rest blade 61 would be adjusted to take care of the different sizes of work pieces in a vertical direction, as will be described in detail later, and toward the regulating wheel.

The block 106 is secured in its several adjustable positions by means of cap screws or the like 55 110 which extend through a slot 111 formed in the upper end of the arm 109. The other end of the arm 109 is also provided with a groove 112 through which clamp screws 113 and 114 extend for securing the arm to the work rest block 60. By this construction the arm 109 may be adjusted 60 relative to the block 60 for disposing the shoe 103 in proper position relative to the work.

In order to vertically adjust the work rest blade 61, the block 60 is shifted relative to the flange 57 together with all the parts carried by this block. Accordingly, the block has journaled therein the opposite ends of a screw 115 having screw threads 116 formed intermediate its ends. 65 A nut 117 is provided in threaded engagement with the screw 116 having extending from opposite sides thereof wings 118 and 119 received in a socket 120 formed in one end of a carriage 121. The carriage 121 is disposed within a comparatively large cavity 122 formed interiorly of the

block 60. The carriage further abuts on its upper surface 123 with the adjacent under surface of the cavity 122. Rotation of the screw 115 will through the threaded portion 116 axially shift the nut 117, which through its engagement by means of the wings 118 and 119 with the carriage 121 axially shifts the said carriage relative to the block 60. 80

The carriage 121 has formed therein diagonal grooves or slots 124 and 125 receiving therein the reduced inclined cam nose portions 126 and 127 of lifting screws or plugs 128. From this it will be seen that as the carriage 121 is axially adjusted a camming action will take place between the cams 126 and 127 and the sides of the cam grooves 124 and 125, thereby moving the carriage vertically in an inclined direction as it is moved along, but moving the block 60 and parts carried thereby in a vertical direction only. 85

To insure the vertical movement only of the block 60, it has projecting from it a pin 129 which extends into the vertical groove 130 formed in the adjacent surface of the flange 57. 90

It is believed that from the foregoing description the several adjustments of the support, guides and overhead shoe will be readily understood and that there has been provided a centerless grinder capable of universal adjustment for taking care of various sizes and types of work pieces without the necessity of removing the parts from the machine and substituting other parts therefor. 95

What is claimed is:

1. In a centerless grinder the combination of a bed, a pair of opposed grinding and regulating wheels carried thereby and forming a grinding throat therebetween, a work rest blade carried by the bed beneath the grinding throat, a housing for one of the wheels, guide plates carried by the housing having their operative surfaces disposed in parallel alignment with the operative surface of said wheel, and means for adjusting the position of the guide plates to dispose the said operative surfaces thereof at an angle to the operative face of the wheel and out of parallelism therewith. 100

2. In a centerless grinder the combination of a bed, a pair of opposed grinding and regulating wheels carried thereby and forming a grinding throat therebetween, a work rest blade carried by the bed beneath the grinding throat, a housing for one of the wheels, guide plates carried by the housing having their operative surfaces aligned with the operative surface of said wheel, and means for adjusting the position of the guide plates to dispose the said operative surfaces thereof out of alignment with the wheel, said adjusting means including a bracket for each guide plate and adjusting members carried by the bracket, and means for adjusting the position of the guide plates and bracket toward and from the wheel housing, comprising a sleeve extending from the bracket, a guide on the housing for the sleeve, and an adjusting screw in operative connection with the bracket sleeve and housing guide. 115

3. In a centerless grinder the combination of a bed, a pair of opposed grinding and regulating wheels carried thereby and forming a grinding throat therebetween, a work rest blade carried by the bed beneath the grinding throat, a housing for one of the wheels, guide plates carried by the housing having their operative surfaces aligned with the operative surface of said wheel, means for adjusting the position of the guide plates to dispose the said operative surfaces thereof out of alignment with the wheel, said adjust- 120 130 135 140 145 150

- ing means including a bracket for each guide plate and adjusting members carried by the bracket, and means for adjusting the position of the guide plates and bracket toward and from the wheel housing, comprising a sleeve extending from the bracket, a guide on the housing for the sleeve, an adjusting screw in operative connection with the bracket sleeve and housing guide, and co-operating means carried by the bracket and housing for holding the bracket and sleeve against movement about the axis of the bracket sleeve.
4. A work rest unit for use with centerless grinders comprising a carriage mounted upon the grinder bed for translation relative thereto, a block carried by the carriage for adjustment relative thereto, means for securing the block in adjusted positions relative to the carriage, and a work rest blade mounted on the block, said means for adjusting the block relative to the carriage comprising a screw rotatably journaled in the block, a nut on the screw, a member associated with the block and movable relative thereto by means of the nut, and co-operating cams associated with the member and carriage whereby movement of the member effects its transverse adjustment.
5. A work rest unit for use with centerless grinders comprising a carriage mounted upon the grinder bed for translation relative thereto, a block carried by the carriage for adjustment relative thereto, means for securing the block in adjusted positions relative to the carriage, and a work rest blade mounted on the block, said means for adjusting the block relative to the carriage comprising a screw rotatably journaled in the block, a nut on the screw, a member associated with the block and movable relative thereto by means of the nut, and co-operating cams associated with the member and carriage whereby movement of the member effects its transverse adjustment, said co-operating cams comprising cam slots formed in the member, and fixed cams projecting from the carriage into operative engagement with the cam slots.
45. An adjustable work support and overhead guide for use with a centerless grinder comprising a carriage mounted on the grinder bed, a supporting block secured to the carriage for movement relative thereto and therewith, a work rest blade supported by the block for supporting a work piece while being operated upon, an overhead guide substantially diametrically opposed to the work rest blade, an arm mounted on the block for adjustment relative thereto and therewith, and an operative coupling between the overhead guide and arm.
7. An adjustable work support and overhead guide for use with a centerless grinder comprising a carriage mounted on the grinder bed, a supporting block secured to the carriage for movement relative thereto and therewith, a work rest blade supported by the block for supporting a work piece while being operated upon, an overhead guide substantially diametrically opposed to the work rest blade, an arm mounted on the block for adjustment relative thereto and therewith, and an operative coupling between the overhead guide and arm, said coupling comprising a guide on the arm disposed at an angle to the general extent of the arm whereby adjustment of the overhead guide varies the vertical and lateral relationship between the said overhead guide and work rest blade.
8. In a grinding machine of the class described the combination of a bed, a pair of opposed grind-
ing and regulating wheels mounted on the bed and forming a grinding throat therebetween, one of said wheels being fixed and the other being movable to vary the size of the grinding throat, a carriage on the bed beneath the grinding throat for movement relative thereto, a work rest blade mounted on the carriage for movement therewith toward and from the operative faces of the grinding and regulating wheels, an overhead guide substantially diametrically opposed to the work rest blade, means securing the guide to the carriage for movement therewith, and additional means for adjusting the position of the guide relative to the carriage to vary its operative position relative to the wheels and laterally of the grinding throat.
9. In a grinding machine of the class described the combination of a bed, a pair of opposed grinding and regulating wheels forming a grinding throat therebetween, a work rest blade disposed beneath the grinding throat for supporting a work piece in simultaneous engagement with the operative faces of the wheels, lateral guides for guiding the work to the throat and from the throat, comprising guide plates, a bracket for each plate, means carried by each bracket at each end of the plates for independently adjusting the ends of the plates to align same with the operative face of the grinding wheel, and means for locking the said plates in adjusted position.
10. In a grinding machine of the class described the combination of a bed, a pair of opposed grinding and regulating wheels forming a grinding throat therebetween, a work rest blade disposed beneath the grinding throat for supporting a work piece in simultaneous engagement with the operative faces of the wheels, lateral guides for guiding the work to the throat and from the throat, comprising guide plates, a bracket for each plate, means supporting the plates for independent adjustment to align same with the operative face of the grinding wheel, means for locking the said plates in adjusted position, and means for disposing the operative face of said guide plates at an angle to the plane of extent of the wheel with which they are associated.
11. In a grinding machine of the class described the combination of a bed, a pair of opposed grinding and regulating wheels forming a grinding throat therebetween, a work rest blade disposed beneath the grinding throat for supporting a work piece in simultaneous engagement with the operative faces of the wheels, lateral guides for guiding the work to the throat and from the throat, comprising guide plates, a bracket for each plate, means supporting the plates for independent adjustment to align same with the operative face of the grinding wheel, means for locking the said plates in adjusted position, and means for disposing the operative face of said guide plates at an angle to the plane of extent of the wheel with which they are associated, said means comprising wedge-shaped members associated with each bracket and forming a base for the guide plate, and means for independently adjusting the wedge members.
12. In a centerless grinder of the class described the combination of a pair of opposed grinding and regulating wheels forming a grinding throat therebetween, a work rest blade subtending the grinding throat and having an inclined operative surface, inclining toward the regulating wheel and forming between them a work receiving trough, an overhead shoe contact-

ing with the work at a point to hold the work in the trough, and means supporting said overhead shoe whereby a single adjustment causes it to approach the work rest blade and simultaneously shift laterally of the throat.

5 13. In a centerless grinder of the class described the combination of a pair of opposed grinding and regulating wheels forming a grinding throat therebetween, a work rest blade subtending the grinding throat and having an inclined operative surface, inclining toward the regulating wheel and forming between them a work receiving trough, an overhead shoe contacting with the work at a point to hold the work in the trough, means supporting said overhead shoe whereby a single adjustment causes it to approach the work rest blade and simultaneously shift laterally of the throat, said supporting means including an arm having an inclined surface inclining laterally with respect to the grinding throat.

10 14. In a work supporting mechanism for use with a centerless grinder the combination of a bed, a carriage mounted thereon for movement relative thereto, a work rest block carried by the carriage for adjustment relative thereto, a work rest blade secured in the block to partake of the movement thereof, an overhead shoe, means securing the overhead shoe to the work rest block whereby it may be adjusted with the block and work rest blade and whereby it may be adjusted independently of the block and blade to vary the distance between the blade and shoe, and additional means for independently adjusting the shoe relative to the supporting means toward the blade and laterally with respect thereto.

15 15. In a work supporting mechanism for use with a centerless grinder the combination of a bed, a carriage mounted thereon for movement relative thereto, a work rest block carried by the carriage for adjustment relative thereto, a work

rest blade secured in the block to partake of the movement thereof, an overhead shoe, means securing the overhead shoe to the work rest block whereby it may be adjusted with the block and work rest blade and whereby it may be adjusted independently of the block and blade to vary the distance between the blade and shoe, additional means for independently adjusting the shoe relative to the supporting means toward the blade and laterally with respect thereto, said means including an arm capable of adjustment with respect to the block to effect an adjustment of the shoe relative to the blade and block, and co-operating inclined guideways on the shoe and arm whereby the shoe is independently adjusted relative to the arm toward and from the blade and laterally with respect thereto.

20 16. In a work supporting unit for use with centerless grinders the combination of a bed, a carriage mounted thereon for translation relative thereto, a rack carried by the bed, a rack pinion in operative engagement with the rack and rotatably supported by the carriage, a worm and worm wheel mechanism carried by the carriage for effecting the operation of the rack, a block adjustably secured to the carriage, an adjusting screw rotatably journaled in the block, a nut on the screw, an axially shiftable member carried by the block in operative engagement with the nut whereby movement of the nut correspondingly axially shifts the member, a cam slot formed in the member, co-operating stationary cams supported by the carriage, means for rotating the screw and effecting operation of the member to cause an adjustment of the block through the cam and cam groove, means for causing a straight line movement of the block relative to the carriage, and means for locking the carriage in adjusted positions.
